(57) **CLAIM**

The ornamental design for a multi-probe cooking thermometer display unit, as shown and described.

DESCRIPTION

FIG. 1 is a top perspective view of a multi-probe cooking thermometer display unit showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof, the bottom view being a mirror image; and,

FIG. 7 is another top perspective view thereof showing temperature probes plugged into the multi-probe cooking thermometer display unit.

The broken line representations of the rear cover portion of the multi-probe cooking thermometer display unit shown in FIGS. 1 and 3-7 and the temperature probes shown in FIG. 7 are for illustrative purposes only and forms no part of our claimed design.
